REACTION GAS TURBINE

Application filed August 27, 1927. Serial No. 215,772.

This invention relates to an internal combustion engine, and more particularly to a gas turbine in which the compression of a gaseous explosive mixture is accomplished under centrifugal action, slugs of a liquid medium being interspersed with charges of said gaseous mixture for this purpose and the latter exploded while under the centrifugal compression, the subsequent expansion of the products of combustion acting on these liquid slugs resulting in a reactive force used in producing rotation of a turbo-element.

A general object of the invention is to provide a pure reaction turbine of this type, and to this end contemplates maintaining the continuity of the liquid slugs discharging from the compressor portion of the apparatus into the explosion chamber portion thereof, as in the provision of a suitable restriction in the path of flow. The invention has for a further object the proportioning of the masses of the liquid slugs and of the charges of the gaseous explosive mixture so that the velocity imparted to the liquid slugs relative to the rotatable element by the expansion of the burned gases in said rotatable element shall be approximately equal and opposite in direction to the peripheral velocity of the rotatable element; also, the provision of suitable means of control of the speed, power and torque developed by the turbine. Additional features of the invention will hereinafter be referred to.

In carrying out the invention, a rotatable turbo-element embodying a series of outwardly directed ducts or tubes is designed to have alternately delivered thereinto a charge of the combustible mixture and a charge of a liquid medium affording slugs interspersed therewith for centrifugally compressing the said mixture and discharging into a terminal combustion chamber forming a continuation of the said ducts. In accordance with the invention, the passageway between a said duct and its explosion chamber is provided with a suitable restriction, which may consist merely in a constriction or Venturi formation of the said passageway or in specific and supplementary means therefor which, however, should not be of such a na-

ture as to destroy the continuity of the passing slugs of liquid. The explosion, preferably, should occur substantially at the moment when this restricted portion is sealed or plugged with a slug of the liquid medium; and the expansion of the products of combustion is to be permitted to continue until the burned gases have expanded nearly or quite to atmospheric pressure.

By proportioning the masses of the liquid slugs to the gaseous mixture such that the velocity imparted to the said slugs relative to the rotatable element through the expansion of the burned gases shall be approximately equal and opposite in direction to the peripheral velocity of the turbo-compressor element, the absolute velocity of said slugs leaving an expansion chamber will be approximately zero, and the apparatus functions as a pure reaction turbine. This eliminates the need of all devices for obtaining correct inter-relationship of rotative speeds as in the case of a combination reaction-impulse turbine.

It is desirable, also, in order to avoid unbalanced forces on the turbine shaft, that there should be provided at least two liquid and two gas admissions per revolution of the turbine, the admission ports being arranged with equal angular intervals, both for the liquid and the gas; but not necessarily with uniform angular spacing of all the admission ports; that is to say, the arrangement shown in which the angular interval between the liquid and the gas admission is substantially equal to the angular interval between the gas and the following liquid admission is merely illustrative and adherence to this arrangement is not necessary.

In order to facilitate the keeping of the slugs substantially intact in their travel to the combustion chamber and while they are being accelerated, said expansion chamber may assume the form of a tube of suitable form and cross-section and as hereinafter disclosed. Moreover, the introduction or entrance to the compression chamber should be at such an angle as to minimize the shock of entry; and to further reduce this shock, the admission of liquid and the gaseous mix-

ture is to be accomplished in a manner such that admission of each compressing slug element is effected soon after the completion of the admission of the corresponding gaseous element.

Provision is made, moreover, for suitably starting the rotation of the turbo-element, and the introduction of the gaseous mixture and the liquid slugs thereto is to be deferred until a considerable rotational velocity has been acquired by the said element so that the work required of the starter mechanism may be a minimum. Also, in the starting operation, the mass ratio of the liquid slug to its gaseous mixture to be compressed is capable of variation so that the starting torque may be increased by providing for an increased ratio of liquid to gaseous mixture. When the turbine is in operation, the said ratio may be decreased as the speed increases to bring about maximum efficiency of operation when the desired operating conditions are reached. The power developed can be controlled advantageously by simultaneous control of both liquid and gaseous mixture, and there is thus afforded great flexibility of operation as well as great simplicity in control.

In the accompanying drawings which illustrate the invention:

Fig. 1 is a longitudinal section taken substantially along the line 1—1, Fig. 2;

Fig. 2 is a transverse vertical section taken substantially along the line 2—2, Fig. 1, and looking in the direction of the arrows;

Fig. 3 is a fragmentary vertical section of a modified form of compression and expansion duct;

Figs. 4 and 5 are fragmentary vertical sections of a duct end and associated explosion chamber illustrating additional means for minimizing back flow of the liquid medium employed, Fig. 4 setting forth the normal condition and Fig. 5 the condition during the explosion period.

Referring to the drawings for a more detailed description of the invention, the novel gas turbine is shown to consist of a rotatable or turbo-element comprising a pair of disks 10 carried by a hub 11 adapted to rotate upon a stationary supporting bearing and distributing member 12. The latter is mounted centrally in the walls of a surrounding casting 13 having a sump or collecting chamber 14 provided therein at the bottom for collecting spent liquid medium, as will hereinafter be more fully set forth. The disks are formed up into or provided with a succession of more or less radially disposed ducts or compressor tubes 15 which extend from the hub portion substantially to the circumference of the rotor member or turbo-element and terminate in an arcuate extension portion 16. As will hereinafter be more fully disclosed, these extension portions con-

stitute explosion chambers for a suitable explosive gaseous medium which is compressed in the said ducts through slugs of a suitable liquid medium such as water, for example. To this end, the said explosion chambers 70 are equipped with suitable ignition means as the spark plugs 17 which are screwed therein in the usual manner, but are intended to be continuously energized. The necessary electric current may be supplied to the spark 75 plug as through slip rings on the shaft and suitable connections such, for example, as shown in the patent to Shaw #523,734, granted July 31, 1894. These plugs, moreover, are preferably so located in their combustion 80 chambers that the explosion of the gaseous mixture occurs substantially at the instant when the inner end of the chamber and outer portion of the compressor duct thereof is most completely plugged with a liquid slug. 85

At their inner ends, the ducts are arranged to communicate with suitable pairs of reservoirs 18 and 19 in the distributing member 12 and adapted to supply respectively a gaseous medium and a liquid medium alternately to 90 said ducts as their inner ends register with corresponding outlet ports 20 and 21 from the reservoirs. In order to avoid unbalanced forces on the turbine shaft, there should be provided at least two liquid and two gas 95 admissions per revolution of the turbine, the admission ports being arranged with equal angular intervals, both for the liquid and the gas, but not necessarily with uniform angular spacing of all the admission ports. 100 In the chamber provided by the said ducts, receiving alternately a charge of gas and a charge of liquid, there is effected the compression of the former under the centrifugal force applied to the slugs of liquid as the 105 turbo-element rotates; and the entrance angle thereto for the introduction of a slug is such as to favor the formation of the liquid slugs and minimize the shock of entry as much as possible. This shock may be further reduced by shaping the outer cylindrical surface of the distributor 12 in manner such that admission of a charge of gas follows soon upon the completion of the admission of a charge of liquid and vice versa. In Fig. 2 110 115 this is indicated by having the distributor periphery following each exit port cylindrical over a distance equal to the width of a duct inlet. From this point the radius of the distributor surface diminishes continuously until it merges in the exit port. 120

The compression chamber or tubular duct, moreover, is not necessarily of uniform cross-section, and may be reduced at its outer end, as shown in Fig. 3, where it merges into an 125 arcuate or circumferentially disposed extension portion 16, which latter may be constructed to flare slightly outwardly. The communication, furthermore, is restricted to assist in checking back flow of a slug, under 130

the action of the explosion pressure, as in constructing the same of Venturi formation as indicated at 22.

If a supplementary restriction is found necessary, this may be provided, for example, as shown in Figs. 4 and 5 of the drawings and wherein there is indicated an obstruction member 23 which is located just beyond the throat of the venturi 22. This obstruction embodies a streamline member or block which is pointed or conical-headed at both ends so as not to destroy the continuity of a slug; and is secured to the side walls of the ducts through webs 24. Immediately beyond the same is mounted for limited reciprocation a cooperating sleeve or valve member 25 which has a frustro-conical passageway 26 therethrough with the smaller end directed toward the obstruction but normally positioned beyond the same, as indicated in Fig. 4. Under the action of the high explosive pressure prevailing in the explosion chamber 16, when a charge of the gaseous medium is ignited, said valve will be forced inwardly toward the obstruction 23, being limited by contact with the shoulder 27 of the Venturi wall, and assumes substantially the position indicated in Fig. 5 in which it more or less surrounds the outer conically headed end of said obstruction member. The restriction normally afforded by the venturi is thus momentarily increased to an appreciable extent to insure against return flow should the Venturi constriction itself be inadequate for this purpose. It is to be understood, however, that no complete closing of the communication is contemplated and no interruption in the continuity of a slug should be permitted to occur as a result. Moreover, the explosion or expansion chamber 16 is to be of such form and cross-section that the liquid slugs are maintained substantially intact while being accelerated therein; and the velocity imparted thereto by the expansion of the burned gases is to be substantially equal and opposite in direction to the peripheral velocity of the centrifugal compressor or turbo-element. This condition may readily be attained by proportioning the masses of the liquid and gaseous charges and, for example, in the manner hereinafter set forth.

In starting the turbine, a conventional self-starter device 28 may be utilized, the same being carried by the casing framing 29 and adapted to mesh into a gear wheel 30 of a sleeve extension of the hub 11. Said gear wheel 30 meshes also with a gear 31 on the power shaft 32 having mounted thereon a pump 33, which pump also is included in a connection 34 shunted about the liquid connection 35 connecting the sump 14 with the liquid reservoirs 19 of the distributing member. A flow controlling member as the valve 36 is included in the connection 35 and a similar valve 37 in the shunt connection 34 so that

the amount of liquid supplied to the reservoirs therethrough may be determined and readily controlled. Provision is made, also, for sending the liquid either directly to said reservoirs, as through the connection 35, or through the pump 33 by which it may be supplied under the desired pressure and thus delivered into the compressing ducts under an initial pressure. This may be conveniently effected through a further valve 39 provided in the Y-fitting 40 at the beginning of the shunt connection, a lever arm or handle 41 being provided for manual operation in shifting the circulation of the liquid. A cooling device for the spent liquid may also be included between the sump and the reservoir, for example, as a radiator 42 located between said sump and the valve 39.

The gaseous medium is supplied from a suitable source, as the carburetor 43, through a connection 44 having a manually controlled valve 45 included therein and whereby the charge of gas supplied to the gas reservoirs 18 may be regulated. A variety of controls is thus afforded; and in starting the turbine with the self-starter 26, the liquid slugs need not be admitted until the turbine has been given a considerable rotational velocity, whereby the work of the self-starter may be kept small. In operation, furthermore, the mass ratio of the liquid plug to the explosive gaseous mixture can be varied by varying either of these masses so as to give a greater ratio of liquid to the gas, and thereby increase the starting torque. The ratio of liquid to gas can equally well be diminished, if desired, as the speed increases so as to give maximum efficiency when the desired operating conditions are attained. The power developed can be controlled advantageously, also, by a simultaneous control of both liquid and gas; and the three elements of control aforesaid will thus be found to give great flexibility in operation and also great simplicity of control.

I claim:

1. The method of doing work on a rotatable element, which comprises centrifugally compressing therein an explosive gaseous medium by slugs of a liquid medium interspersed therewith, exploding the compressed gaseous medium and expanding it approximately to atmospheric pressure in the presence of a slug to expel the same from the rotatable element, and proportioning the mass of a slug to the mass of a corresponding gaseous charge such that the velocity imparted to the former by the explosion and expansion of the latter is substantially equal and opposite in direction to the peripheral velocity of the rotatable element, whereby the slug issues with negligible absolute velocity.

2. The method of doing work on a rotatable element, which comprises centrifugally

- compressing therein an explosive gaseous medium by slugs of a liquid medium interspersed therewith, exploding the compressed gaseous medium and expanding it approximately to atmospheric pressure in the presence of a slug to expel the same from the rotatable element, and maintaining substantially intact the said slugs, until expelled, with restriction of the flow thereof.
10. 3. The method of doing work on a rotatable element, which comprises centrifugally compressing therein an explosive gaseous medium by slugs of a liquid medium interspersed therewith, exploding the compressed gaseous medium and expanding it approximately to atmospheric pressure in the presence of a slug to expel the same from the rotatable element, and maintaining substantially intact the said slugs until expelled, with restriction of the flow thereof and momentary increase of the restriction.
4. The method of doing work on a rotatable element, which comprises centrifugally compressing therein an explosive gaseous medium by slugs of a liquid medium interspersed therewith, exploding the compressed gaseous medium and expanding it approximately to atmospheric pressure in the presence of a slug to expel the same from the rotatable element, and maintaining substantially intact the said slugs, until expelled, with restriction of the flow thereof and momentary increase of the restriction at the instant of explosion of the gaseous charge.
35. 5. The method of doing work on a rotatable element, which comprises introducing alternately thereto a charge of an explosive gaseous medium and a slug of a liquid medium, the latter being introduced soon after completion of the introduction of the former and centrifugally compressing the same, exploding the compressed gaseous medium and expanding it approximately to atmospheric pressure in the presence of a slug to expel the same from the rotatable element, and proportioning the mass of a slug to the mass of a corresponding gaseous charge such that the velocity imparted to the former by the explosion of the latter is substantially equal and opposite in direction to the peripheral velocity of the rotatable element whereby the slug issues with negligible absolute velocity.
6. A combustion turbine, comprising a rotatable turbo-element, distributing means for a gaseous medium and a liquid medium, radially disposed centrifugal compressing means to receive from the distributing means alternate charges of the gaseous medium and the liquid medium and compressing the former by the latter, circumferentially disposed means to receive both media and provided with respective discharge orifices, flow restricting means between the compressing means and the circumferentially disposed means, and ignition means located in the circumferentially disposed means for exploding the charge of the gaseous medium.
7. A combustion turbine, comprising a rotatable turbo-element having a succession of outwardly directed ducts, means to introduce alternate charges of a gaseous and a liquid medium into the ducts and the former being compressed therein by the latter, circumferentially disposed means in communication with the respective ducts and having discharge orifices, ignition means located therein for exploding a charge of the gaseous medium, and means momentarily to constrict each duct.
8. A combustion turbine, comprising a rotatable turbo-element having a succession of outwardly directed ducts, means to introduce alternate charges of a gaseous and a liquid medium into the ducts and the former being compressed therein by the latter, circumferentially disposed means in communication with the respective ducts and having discharge orifices, ignition means located therein for exploding a charge of the gaseous medium, and means momentarily to constrict each duct substantially at the junction of the circumferentially disposed means with the duct.
9. A combustion turbine, comprising a rotatable turbo-element having a succession of outwardly directed ducts, means to introduce alternate charges of a gaseous and a liquid medium into the ducts and the former being compressed therein by the latter, circumferentially disposed means in communication with the respective ducts and having discharge orifices, ignition means located therein for exploding a charge of the gaseous medium, and slideable means actuated by the explosive force of a charge of the gaseous mixture momentarily to constrict each duct.
10. A combustion turbine, comprising a rotatable turbo-element having a succession of outwardly directed ducts, means to introduce alternate charges of a gaseous and a liquid medium into the ducts and the former being compressed therein by the latter, arcuate extensions of the respective ducts and affording combustion chambers, ignition means located therein, and flow restricting means located at the entrance of each arcuate extension.
11. A combustion turbine, comprising a rotatable turbo-element having a succession of outwardly directed ducts, a means to introduce alternate charges of a gaseous and a liquid medium into the ducts and the former being compressed therein by the latter, arcuate extensions of the respective ducts and affording combustion chambers, ignition means located therein, flow restricting means located at the entrance of an arcuate extension and including a reciprocal valve piece having a tapered passageway therethrough, and an obstruction member mounted in the

arcuate extension adapted to fit into the smaller end of the tapered passageway to reduce its effective cross-sectional area.

12. A combustion turbine, comprising a rotatable turbo-element having a succession of outwardly directed ducts, means to introduce alternate charges of a gaseous and a liquid medium into the ducts and the former being compressed therein by the latter, arcuate extensions of the respective ducts and affording combustion chambers, ignition means located therein, flow restricting means located at the entrance of an arcuate extension and including a reciprocal valve piece having a tapered passageway therethrough, and a fixed streamline obstructing member having a conical head adapted to cooperate with the hollow sliding valve piece.

13. A combustion turbine, comprising a rotatable turbo-element having a succession of outwardly directed ducts, means to introduce alternate charges of a gaseous and a liquid medium into the ducts and the former being compressed therein by the latter, arcuate extensions of the respective ducts and affording combustion chambers, said ducts including a Venturi portion, ignition means located in the extensions, and additional flow restricting means located at the entrance of each arcuate extension.

14. A combustion turbine, comprising a rotatable turbo-element having a succession of outwardly directed ducts, means to introduce alternate charges of a gaseous and a liquid medium into the ducts and the former being compressed therein by the latter, arcuate extensions of the respective ducts and affording combustion chambers, said ducts including a Venturi portion, ignition means located in the extensions, additional flow restricting means located at the entrance of each arcuate extension having a streamlike obstruction mounted beyond the throat of the Venturi portion and a slidable sleeve mounted in the arcuate extension with frusto-conical passageway therethrough, the smaller end thereof being adapted to surround the outer end of the said obstruction when the pressure in a combustion chamber exceeds that prevailing in a corresponding duct.

15. A combustion turbine, comprising a rotatable turbo-element having a succession of outwardly directed ducts, a means to introduce alternate charges of a gaseous and a liquid medium into the ducts and the former being compressed therein by the latter, the ducts diminishing in cross-sectional area toward their outer ends and terminating in a Venturi portion, arcuate extensions communicating therewith, of increasing cross-sectional area toward their outer ends and constituting explosion chambers, and ignition means located therein for exploding a charge of the gaseous medium.

16. A combustion turbine, comprising a rotatable turbo-element having a succession of outwardly directed ducts, each having a combustion chamber, ignition means for exploding a charge in each combustion chamber, a surrounding casing into which said ducts are adapted to discharge, and having a sump at the bottom for collecting the spent liquid, a distributing member about which said turbo-element rotates and provided with ports adapted to register with the inner ends of the said ducts, a source of supply of gaseous explosive medium, a connection therefrom to the distributing member, a connection from said sump to said distributing member, a shunt about said sump connection, a pump driven by the turbo-element and located in the shunt, and means to divert the liquid from the sump through the shunt connection to supply the same under pressure to the distributing member.

17. A combustion turbine, comprising a rotatable turbo-element having a succession of outwardly directed ducts, each having a combustion chamber, ignition means for exploding a charge in each combustion chamber, a surrounding casing into which said ducts are adapted to discharge and having a sump at the bottom for collecting the spent liquid, a distributing member about which said turbo-element rotates and provided with ports adapted to register with the inner ends of the said ducts, a source of supply of gaseous explosive medium, a connection therefrom to the distributing member, a connection from said sump to said distributing member, a shunt about said sump connection, flow controlling means in said connections, a pump driven by the turbo-element and located in the shunt, and means to divert the liquid from the sump through the shunt connection to supply the same under pressure to the distributing member.

18. A combustion turbine, comprising a rotatable turbo-element having a succession of outwardly directed ducts, each having a combustion chamber, ignition means for exploding a charge in each combustion chamber, a surrounding casing into which said ducts are adapted to discharge, and having a sump at the bottom for collecting the spent liquid, a distributing member about which said turbo-element rotates and provided with ports adapted to register with the inner ends of the said ducts, a source of supply of gaseous explosive medium, a connection therefrom to the distributing member, a connection from said sump to said distributing member, and cooling means located therein.

19. A combustion turbine, comprising a rotatable turbo-element having a succession of outwardly directed ducts, each having a combustion chamber, ignition means for exploding a charge in each combustion chamber,

ber, a surrounding casing into which said ducts are adapted to discharge and having a sump at the bottom for collecting the spent liquid, and a distributing member about which said turbo-element rotates and provided with a chamber for supplying a liquid medium and a chamber for a gaseous explosive medium, said chambers having outlet ports adapted to register with the inner ends of the said ducts, a port for admitting the liquid medium being uncovered soon after completion of the uncovering of a port for the gaseous medium.

20. A reaction internal combustion turbine comprising a rotatable turbo-element having tangential rearwardly directed discharge outlets, means for feeding to said outlets slugs of liquid with charges of an explosive mixture behind said slugs and electric ignition means for igniting the mixture to expel said slugs rearwardly creating a reaction impulse to rotate the turbo-element.

21. In apparatus for generating energy the combination with rotatable means for centrifugally compressing a gaseous medium by slugs of a liquid medium interspersed therewith, of an explosion chamber carried by the rotatable means and means for exploding the compressed gaseous medium while under centrifugal compression in said chamber.

22. In apparatus for generating energy the combination with rotatable means for centrifugally compressing a gaseous medium by slugs of a liquid medium interspersed therewith, of means for igniting said mixture while under centrifugal pressure in said rotatable means and reaction means for converting the explosion of said medium into energy.

23. A combustion reaction turbine comprising a rotatable reaction element having a radial passage and a combustion chamber in which said passage terminates, and means for admitting alternate charges of gas and liquid to said radial passages.

LIONEL S. MARKS.
